SEWING MACHINE WORK SUPPORTING PLATE

Sixten Andersson-Sason, Solna, Sweden, assignor to Husqvarna Vapenfabriks Aktiebolag, Huskvarna, Sweden

Application November 8, 1957, Serial No. 78,382

Term of patent 14 years

(Cl. D70—2)

The figure is a perspective view of a sewing machine work supporting plate showing my new design.

The dotted line showing of a sewing machine head is for illustrative purposes only.

I claim:

The ornamental design for a sewing machine work supporting plate, as shown and described.
